UNITED STATES PATENT OFFICE.

ANDREW WILLIAM STOREY, OF MOSTON, NEAR MANCHESTER, ENGLAND.

FUSIBLE LINK.

No. 811,256.

specification of Letters Patent.

Patented Jan. 30, 1906.

Application filed May 12, 1905. Serial No. 260,125.

To all whom it may concern:

Be it known that I, ANDREW WILLIAM STOREY, engineer, a subject of the King of Great Britain, residing at Old Hall Road, Moston, near Manchester, in the county of Lancaster, England, have invented a new and useful Improved Fusible Link, of which the following is a specification.

My invention relates to an improved fusible link applicable for certain forms of automatic fire-extinguishing sprinklers, for fire-proof doors, and for other similar purposes; and the chief object of my improvements is to protect the sensitive solder of the fusible link against oxidation.

In carrying my invention into effect I form the fusible link in two parts connected together by a screw-joint. One part consists of a small cylinder formed of a suitable metal, preferably copper or brass, and then filled with sensitive solder, which is afterward drilled out, so as to leave a thin lining of solder, in which a screw-thread is then cut. The second part of the link consists of a small plug, screw-threaded to correspond with the thread in the cylinder.

In the accompanying sheet of drawings, Figure 1 is a side elevation, and Fig. 2 an end elevation, of my improved fusible link; and Fig. 3 is a longitudinal vertical section of Fig. 1. Fig. 4 is a front elevation, Fig. 5 a side elevation, and Fig. 6 a plan, of an automatic fire-extinguishing sprinkler with my improved fusible link applied thereto. Figs. 7, 8, and 9 are similar views to Figs. 4, 5, and 6, respectively, of another construction of automatic sprinkler sealed by two of my improved fusible links.

Referring first to Figs. 1, 2, and 3, 1 denotes a cylinder forming the first part, and 2 the small screw-threaded plug forming the second part, of my improved fusible link. The part 1 is formed of suitable metal and is filled with sensitive solder, which is then drilled out, so as to leave a thin lining 3 of the solder, in which a screw-thread is then cut corresponding with the thread on the plug 2. The parts 1 and 2 are coupled up by screwing the plug 2 into the cylinder 1, as shown. Any convenient device is adopted to prevent the solder 3 being drawn out of

the cylinder 1. For example, as shown in Fig. 3, the cylinder is of largest diameter at its closed end and gradually tapers to its smallest diameter at its open end.

The improved fusible link is applicable to certain forms of automatic sprinklers in which a valve is held to its seating by an arrangement of levers, also for holding back fireproof doors and for like purposes, in which increase of heat resulting from fire will melt the sensitive solder contained in the cylindrical part of the link, and thus allow the parts to separate under the strain or weight upon them.

In Figs. 4 to 9, inclusive, I show two forms of automatic sprinklers to illustrate the application of my improved fusible link. In the first arrangement, Figs. 4 to 6, the link *a* is shown confining the extremities of two levers *b b*, which when in the position shown in the drawings hold the valve *c* to its seating in the usual way. On an outbreak of fire the fusion of the sensitive solder in the link will break the screw-joint and allow the parts to separate and the sprinkler to open. In the second arrangement, Figs. 7 to 9, two of the links *a* are employed to confine a spring-piece *f* and hold the valve *e* to its seating.

Having now particularly described and ascertained the nature of my said invention and in what manner the same is to be performed, I declare that what I claim, and desire to secure by Letters Patent of the United States, is—

A fusible link comprising two parts, one consisting of a cylinder 1 having a tapered interior, a sensitive solder lining for said cylinder having its exterior tapered and having a screw-threaded bore and the other part 90 consisting of a screw-threaded plug fitting the threaded lining, said second part having a projecting portion closing the end of the cylinder so as to completely cover the sensitive solder.

In testimony whereof I have signed my name to this specification in the presence of two subscribing witnesses.

ANDREW WILLIAM STOREY.
